CLAIM

The ornamental design for a home theater assembly including video display panel suspendable on associated wall surface and operably connectable to audio components contained within underlying cabinet, as shown and described.

DESCRIPTION

FIG. 1 is a rear perspective view of a home theater assembly including video display panel suspendable on associated wall surface and operably connectable to audio components contained within underlying cabinet showing my new design;

FIG. 2 is a front elevational view thereof;

FIG. 3 is a right side elevational view thereof;

FIG. 4 is a left side elevational view thereof;

FIG. 5 is a top plan view thereof; and,

FIG. 6 is a bottom plan view thereof.

The broken lines shown in FIGS. 1-6 are for illustrative purposes only and form no part of the claimed design.
